APPARATUS FOR CLEANSING CONDUITS

Steve Uroukoff, Harvey, Ill.

Application August 26, 1936, Serial No. 97,870

3 Claims. (Cl. 225—12)

This invention relates to apparatus or devices for cleansing conduits, and more particularly pipes and coils such as employed in cooling or dispensing apparatus for beer and other beverages.

It is generally recognized that the flavor of beer, as well as several other beverages, is rather delicate and may readily become impaired by the presence of foreign or unsanitary matter or accumulations in the pipe or coils through which it is dispensed. To obviate this difficulty it has been found necessary to cleanse the pipes and coils at frequent periodic intervals.

There has been heretofore devised several different types of devices directed toward the solution of this problem, and in the majority of instances such devices do not effectively dislodge and remove the slime and accumulations in the pipes and coils. In some of the prior art devices of the type which employ water and a cleansing compound, the compound is frequently wasted in that the cleaning solution is not fully utilized to accomplish its function of loosening, dissolving and carrying away the slime, dirt, and so forth, in the pipes and coils, before it is discharged.

One of the objects of this invention is to provide an improved and simplified apparatus of the character indicated which is capable of effectively and expeditiously cleansing pipes and coils.

Another object of this invention resides in the provision of improved apparatus of this type which is constructed so that the cleansing fluid may be caused to flow or surge back and forth, under pressure, through the pipes and coils for a predetermined period of time, and wherein the apparatus is provided with indicating means whereby the color of the solution may be easily observed at any time during operation of the apparatus so that the condition of the pipes and coils may be ascertained.

A further object is to provide improved apparatus for the purpose indicated which is of relatively simple and compact construction and which is economical to manufacture.

A still further object of this invention is to provide improved cleansing apparatus of the type employing a solution of water and a cleansing compound which is constructed so as to require the use of a minimum quantity of cleansing compound while permitting maximum utilization of the compound for effecting the cleansing operation.

Other objects and advantages of this inven-

tion will be apparent from the following description taken in connection with the accompanying drawings in which:

Fig. 1 is a front elevational view, in partial section, of the apparatus embodying the present invention, in operation upon a diagrammatically illustrated conventional type of installation for cooling and dispensing beverages.

Fig. 2 is a vertical, medial, section through the control apparatus, taken as indicated at lines 2—2 on Fig. 1.

Fig. 3 is a vertical, medial, section, taken as indicated at lines 3—3 on Fig. 2.

Fig. 4 is a transverse section through the valve proper, taken as indicated on line 4—4 on Fig. 3.

Fig. 5 is a sectional view similar to Fig. 4 showing the valve in a different position of adjustment.

Fig. 6 is a transverse sectional view, taken as indicated at line 6—6 on Fig. 2.

The apparatus constituting the present invention includes a control device indicated generally at 10 which in Fig. 1 is illustrated in connection with a conventional type of beverage cooling chest 11 which is herein shown as including a pair of coils of tubing 12 and 13 in which the beverage is contained during the cooling period. It is to be understood that these coils are preferably formed of metal possessing non-corroding characteristics. The cooling chest 11 is generally provided with a sink 14 having discharge or drain conduit 15, and as is well understood there is generally superimposed upon the ledges of the sink a foraminated support (not shown) on which glasses or other receptacles are supported while being filled with beverage. The openings in the support are provided for the purpose of permitting drainage into this sink of any overflow or drippings of the beverage. As shown in the drawings the chest is provided with two faucets 16 and 17 which are connected respectively to the upper ends of the cooling coils 12 and 13 and there is generally provided at or adjacent the chest a water faucet 18, which is connected to a suitable source of supply. It is to be understood that the faucet 18 supplies water under pressure, the force of which is employed in effecting the cleansing of the pipes and coils, and in the present apparatus I employ a solution of water and a suitable cleansing compound, which is forcibly moved back and forth through the pipes and coils for dislodging, dissolving and removing slime and dirt and other accumulations.

It is to be understood that the lower ends 55

of the coils 12 and 13 are usually connected by suitable conduits to barrels or other receptacles containing the beverage to be dispensed. In some instances the barrels may be located at 5 places quite remote from the cooling chest, such as for example in the basement. When the chest is of the type employing more than one cooling coil, said coils, for purpose of cleansing are preferably connected up in series so that 10 they may be simultaneously cleaned by a single operation of the apparatus constituting this invention. In the illustrated example of the chest shown in Fig. 1 the lower ends of the coils 12 and 13 are connected together by appropriate pieces 15 of conduit and couplings indicated diagrammatically at 19.

The control device shown in detail in Figs. 2 to 6 inclusive includes a body 21, preferably of metal, formed with an upwardly open compound 20 receiving chamber 22. Threaded on the upper end of said body for closing the chamber is a removable cap indicated at 23. The lower portion of the body which also communicates with the chamber 22 is formed with a frusto conical 25 valve seat 25 for a rotary tapered valve element 26. The lower end of said body is provided with a bottom plate 27 secured in place by means of screws 28. Said plate is formed with a depending threaded projection 29 on which is mounted a 30 flanged base 30, firmly secured against the under side of the plate 27 by a nut 31. Threaded in said depending portion 29 is an adjustment screw 33 the upper end of which supports a spherical body 34 in contact with a concave socket 35 formed in the bottom of a centrally located projection 36 on the lower end of the valve element 26, as may be seen in Figs. 2 and 3. By virtue 35 of the screw 33 the valve 26 may be adjusted in its seat for a proper rotary fit and seal against the passage of fluid.

The upper end of the valve element is formed with an upwardly open cavity 38 which constitutes a part of the chamber 22 and is adapted to receive the cleansing compound, preparatory to setting the apparatus in operation. The wall of the valve surrounding the cavity 38 is formed with a pair of apertures or ports 26a and 26b, opening into the cavity and which are adapted to be alternately aligned in registered relation respectively with the ports 41 and 42, which open 50 into conduits 43 and 44 respectively, through which conduits the solution passes to and from the pipes and coils that are to be cleaned. The conduits 43 and 44 are formed as projections integral with the side walls of the body 21, and as seen in Fig. 2 of the drawings said projections and conduits are formed so that the conduits travel first in an upwardly and thence a downwardly direction. Associated with the ends of each of said projections is means hereinafter described in detail for visually indicating the character of the solution, which in turn indicates the condition of cleanliness of the pipes and coils.

Said ports 26a, 26b, 41 and 42 are disposed in substantially the same horizontal planes, and located in said planes intermediate ports 41 and 42 is a port 45 of a conduit 46, for discharging the solution into the sink 14 after completion of the cleansing operation. The outer wall of the 65 valve element is formed with a duct 26c which in alternate positions of adjustment of the valve connects the part 45 of the discharge conduit with either of the ports 41 or 42. Rigidly connected with the lower end of valve element 26 is a 70 laterally extending handle 26d which projects 75

through a slot 21a formed in the lower portion of the wall of the body 21. The ends of the slot serve as stops for limiting the movement of the handle 26d in either direction, corresponding to either operative position of adjustment of the valve element. As seen in Fig. 4, the port 26a of the valve is aligned with port 41 of conduit 43, while the transverse duct 26c connects port 42 with the port 45 of the discharge conduit. In the position of adjustment shown in Fig. 5, it may 10 be understood that the fluid is flowing in a direction opposite to that shown in Fig. 4. In this position the port 26b is in registration with port 42 while the duct 26c connects port 41 with the port 45 of the discharge conduit.

Mounted above the discharge conduit 46 is a 15 water supply conduit 48 which opens directly into the upper portion of the chamber 22. It is to be understood that the water as supplied through said conduit 48, becomes admixed with a chemical 20 compound in the chamber, and that the pressure of said water is utilized as the force for moving the chemical solution back and forth through the pipes and coils.

The visual indicating means connected to the 25 respective conduits 43 and 44 each include a pair of spaced apart coupling members 51 between which is interposed in sealed relation a tubular transparent receptacle 52. Snugly mounted within and adjacent the lower end of each of said receptacles, is a fitting 53 the upper end of which is provided with a screen 54. Now, as the solution passes through the respective conduits 43 and 44 to or from the coils or pipes being operated upon the color of the solution may be readily observed in the receptacle 52. To further effect dislodgment and removal of slime and other accumulation in the pipes and coils I provide one or more small bodies of resilient material indicated at 55, which may be of sponge rubber or the like, and which bodies are driven through the pipes and coils, by the pressure of the water, simultaneously with the movement of the cleansing solution through the pipes and coils. After the resilient bodies 55 have been moved through the pipes and coils they return to the opposite receptacle 52 and are retained therein by the screen 54.

For convenience in using this apparatus the conduits 46 and 48 emanating from the body 21 are formed with annular corrugations so as to provide sealing engagement for the ends of flexible conduits such as rubber hose. As may be seen in the drawings the water supply conduit 48 is connected to a flexible conduit 60, the opposite end of which may be connected to the water faucet 18 and the discharge conduit 46 is connected to a flexible conduit 61 the opposite end of which may be connected or disposed in a manner for discharging, and as shown in Fig. 1 of the drawings the free end of conduit 61 is disposed in the sink 14 adjacent the discharge pipe 15. The continuation of the conduits 43 and 44 through the visible indicating devices is in the form of couplers 62 and 63 connected to the couplings 51 and which in turn are connected respectively to the respective ends of flexible conduits or hoses 64 and 65. As shown in Fig. 1 the conduit 64 is connected to the faucet 16 while the conduit 65 is connected to the faucet 17.

After the apparatus is connected as above mentioned, with the cooling coil or coils disconnected from their barrels and connected together in series, it is first desirable to turn on the water supply by faucet 16 and flush the coils and pipes merely by the use of water, either warm, hot or

cold, so as to remove the residual beer and foam from the system. The next step is to temporarily shut off the water and disconnect the apparatus, remove cap 23 and place the proper quantity of cleansing compound in the chamber 22 and replace the cap 23. Then upon turning on the supply of water from faucet 18 the water enters through conduit 60, through conduit 48 into chamber 22 in contact with the cleansing compound, and when the valve element is in a position of adjustment shown in Fig. 4 the initial quantity of water is admixed with the cleansing compound and passes through ports 26a and 41 through conduit 43 into the hose 64 through faucet 16, and thence through the coils 12 and 13, returning through the faucet 17 by way of the hose 65 to the conduit 44, which in turn is connected by duct 26c of the valve element to the discharge conduit 46. Such admixture of cleaning compound and the initial quantity of water is propelled through the conduits, coils, etc., by the pressure of the column of water which follows up the admixture. However before any appreciable amount of fluid is discharged through conduit 46 the operator reverses the position of adjustment of the valve to that shown in Fig. 5 and by virtue of which adjustment the solution is caused to travel in reverse direction by the pressure of water entering ports 26b, and 42, and acting on the solution in conduit 44. The solution is then forcibly moved back through the coils 12 and 13, through faucet 16 returning by way of the hose 64, through the conduit 43, and when the solution again arrives at the conduit 43 the valve is again reversed. This operation is repeated a number of times until the condition of the solution indicates that the pipes and coils are thoroughly cleansed, and this is ascertained by the condition of the solution which may be readily observed at any time through the glasses 52, of the indicating device. The glass receptacles indicate to the operator the time when the solution has completely passed through the coils and is returning to the control device, so that as the solution commences to enter the temporarily empty receptacle 52 the operator promptly reverses the position of adjustment of the valve.

To assist the cleansing compound in loosening and removing slime and other accumulations from the inner surface of the pipes and coils, the resilient bodies 55 move with the body of cleansing solution through the pipes and coils back and forth during the successive reversal of movement of the body of cleansing solution by the manipulation of the valve 26. When the condition of the fluid as observed through one of the receptacles 52 is such as to definitely indicate that the pipes and coils are thoroughly cleansed, the valve may be permitted to remain in either of the positions of adjustment shown in Figs. 4 and 5 so that the cleansing solution may be removed from the system and discharged through the conduits 46 and 61 into the sink 14. After the cleaning fluid has been discharged, it is desirable to adequately flush the system with clear water, and desirably the apparatus should be manipulated so as to cause clear water to surge back and forth through the pipes in the same manner as the cleansing solution so as to thoroughly remove from the pipes or coils any of the cleansing solution or loose particles of foreign matter. After this is accomplished the hoses or conduits, 60, 64 and 65 may be disconnected from the respective faucets and the coils 12 and

13 connected at their lower ends to the barrels or other receptacles containing the beverages.

Although I have herein shown and described a specific embodiment of my invention, manifestly it is capable of modification and rearrangement 5 without departing from the spirit and scope thereof. I do not, therefore, wish to be understood as limiting my invention to the specific construction herein disclosed, except as it may be so limited in the appended claims. 10

I claim as my invention:

1. Apparatus of the character described, comprising a chambered body adapted to contain a cleaning compound, a removable cover for one end of said chamber, a tapered valve seat formed 15 in said chamber adjacent its opposite end, and a rotary cup shaped valve plug therefor, the cavity of said plug constituting the bottom of said chamber, a pair of pipe conduits extending from said chambered body adapted to be connected 20 to the opposite end of pipes or coils to be cleaned, or to the ends of a plurality of pipes connected in series, the ports of said conduits extending through the valve seat portion of said chamber, a discharge conduit extending from said body 25 having its port extending through the valve seat portion, and a water inlet conduit having its port extending through the upper portion of said body and adapted to admit water under pressure to said chamber and to cleaning compound contained therein, the said valve plug having two 30 ports extending through the walls thereof and adapted to alternately register with the port of one pipe conduit or the port of the other pipe conduit and admit water thereto, and a non-chamber-communicating slot on the exterior of 35 said valve plug adapted to alternately form a communicating passage between the port of one or the other of the pipe conduits and the port of the discharge conduit whereby when one of the 40 ports in the plug is in registry with one of the ports leading through the seat to a pipe conduit, the non-chamber-communicating slot establishes communication between the other pipe conduit and the discharge conduit, and on movement of 45 the plug the other port in the plug communicates with the other pipe conduit and the non-chamber-communicating slot establishes communication between the first mentioned pipe conduit and the discharge conduit, the said valve plug being 50 adapted to be limitedly rotated in opposed directions to effect the aforesaid alternate registration whereby increments of liquid are continuously introduced through the chamber alternately to the opposite ends of a pipe or coil connected 55 thereto and increments of liquid are continuously discharged from the opposite end of said pipe or coil through the discharge conduit of said chamber.

2. Apparatus of the character described comprising a chambered body adapted to contain a cleaning compound, a removable cover for one end of said chamber, a tapered valve seat formed in said chamber adjacent its opposite end, and a rotary cup shaped valve plug therefor, the cavity of said plug constituting the bottom of said chamber, said valve plug having an axial aligned concave socket at the exterior large end thereof and a spherical element seated in said socket, a screw threaded in said body 60 and contacting said spherical element to firmly maintain the valve plug in the valve seat, a pair of pipe conduits extending from said chambered body adapted to be connected to the opposite end of pipes or coils to be cleaned, or to the ends 65 70 75

of a plurality of pipes connected in series, the ports of said conduits extending through the valve seat portion of said chamber, a discharge conduit extending from said body having its port 5 extending through the valve seat portion and a water inlet conduit having its port extending through the upper portion of said body and adapted to admit water under pressure to said chamber and to cleaning compound contained 10 therein, the said valve plug having two ports extending through the walls thereof and adapted to alternately register with the port of one pipe conduit or the other port of the other pipe conduit and admit water thereto, and a non-chamber-communicating slot on the exterior of said 15 valve plug adapted to alternately form a communicating passage between the port of one or the other of the pipe conduits and the port of the discharge conduit whereby when one of the ports 20 in the plug is in registry with one of the ports leading through the seat to a pipe conduit, the non-chamber-communicating slot establishes communication between the other pipe conduit and the discharge conduit, and on movement of 25 the plug the other port in the plug communicates with the other pipe conduit and the non-chamber-communicating slot establishes communication between the first mentioned pipe conduit and the discharge conduit, the said valve 30 plug being adapted to be limitedly rotated in opposed directions to effect the aforesaid alternate registration whereby increments of liquid are continuously introduced through the chamber alternately to the opposite ends of a pipe 35 or coil connected thereto and increments of liquid are continuously discharged from the opposite end of said pipe or coil through the discharge conduit of said chamber.

3. Apparatus of the character described comprising a chambered body adapted to contain a cleaning compound, a removable cover for one end of said chamber, a tapered valve seat formed in said chamber adjacent its opposite end, and a rotary cup shaped valve plug therefor, the cavity of said plug constituting the bottom of 40 said chamber, a pair of pipe conduits extending from said chambered body adapted to be connected to the opposite end of pipes or coils to be cleaned, or to the ends of a plurality of pipes connected in series, the ports of said conduits extending through the valve seat portion of said chamber, visual indicating means connected in 45 said pipe conduits adjacent said body, a resilient element adapted to be movable back and forth through said pipes or coils by the pressure of liquid supplied through said chamber and means in each indicating means for arresting movement of the resilient body in one direction, a discharge conduit extending from said body having its port extending through the valve seat portion, and a water inlet conduit having its port extending through the upper portion of said body and adapted to admit water under pressure to said chamber and to cleaning compound contained 50 therein, the said valve plug having two ports extending through the walls thereof and adapted to alternately register with the port of one pipe conduit or the port of the other pipe conduit and admit water thereto, and a non-chamber-communicating slot on the exterior of said valve plug adapted to alternately form a communicating passage between the port of one or the other of the pipe conduits and the port of the discharge conduit whereby when one of the ports in the plug is in registry with one of the ports leading through the seat to a pipe conduit, the non-chamber-communicating slot establishes communication 55 between the other pipe conduit and the discharge conduit, and on movement of the plug the other port in the plug communicates with the other pipe conduit and the non-chamber-communicating slot establishes communication between the first mentioned pipe conduit and the discharge conduit, the said valve plug being adapted to be limitedly rotated in opposed directions to effect the aforesaid alternate registration whereby increments of liquid are continuously introduced through the chamber alternately to the opposite ends of a pipe or coil connected thereto and increments of liquid are continuously discharged from the opposite end of said pipe or coil through the discharge conduit of said chamber.

STEVE UROUKOFF.
